UNITED STATES PATENT OFFICE.

GEORGE EDMOND DENMAN, OF FRUITVALE, CALIFORNIA.

LIQUID-FUEL BURNER.

1,114,450.

Specification of Letters Patent.

Patented Oct. 20, 1914.

Application filed February 6, 1914. Serial No. 816,906.

To all whom it may concern:

Be it known that I, GEORGE EDMOND DENMAN, a citizen of the United States, and a resident of Fruitvale, in the county of Alameda and State of California, have invented 5 a new and Improved Liquid-Fuel Burner, of which the following is a full, clear, and exact description.

This invention relates to burners through 10 which liquid fuel is forced out into a fine, evenly subdivided, spray the particles of which are made to intermingle with the fluid used and by means of which fluid the atomizing of the liquid fuel is obtained.

15 The object thereof is to provide an inexpensive, simple and efficient burner which can be easily cleaned, inspected and repaired.

Reference is to be had to the accompanying 20 drawings forming a part of this specification in which similar characters of reference indicate corresponding parts in all the views and in which:

Figure 1 is a longitudinal axial section of 25 an embodiment of my invention; Fig. 2 is a vertical, central section through the tip on lines 2—2, Fig. 1; Fig. 3 is a horizontal cross section through the tip on lines 3—3, Fig. 1; Fig. 4 is a horizontal cross section 30 on line 4—4, Fig. 1; and Fig. 5 is a vertical cross section on line 5—5, Fig. 1.

Before proceeding to a more detailed description of my invention, it must be clearly understood that the device herein disclosed 35 is an improvement on my application, Serial No. 739,634, filed January 2, 1913, Patent No. 1,086,998. It differs from the other structure in the formation of the tip body proper.

40 Referring to the drawings, 7 represents the tip proper having a funnel portion 8, the stem 9 of which is threaded exteriorly and received in an elbow 10, and which stem registers with the central passage 11 in said elbow. The upper portion 12 of the tip which forms a continuation of the funnel portion is cylindrical and threaded 45 interiorly at its upper end wherein it is engaged by a plug 13 plugging said tip at said end. The cylindrical portion 12 of the tip is provided with a slot 14 disposed perpendicular to the axis of the tip and intended as an outlet from said tip for the fuel admitted to the tip through the 50 passage 11 of the elbow. In lieu of the slot 14, an opening of any shape can be

made. The elbow 10 is also provided with a plurality of passages 15 disposed about the central passage 11. A sleeve 16 threaded on the exterior end of the elbow 10 surrounds the funnel portion 8 of the tip 7 and engages with the edge of the non-threaded end 60 a flange portion 17 provided on the cylindrical portion 12 of the tip, thus forming a closed chamber 18 above the elbow 10. 65 and about the funnel portion 8 of the tip. The passages 15 form the fluid outlet into said chamber, which chamber communicates with the tip 7 by means of apertures 19 formed in the funnel portion 8 of said tip 70 adjacent the stem 9. The liquid fuel is supplied through an inner tube or casing connected to the elbow 10 and in register with the passage 11 of said elbow. The fluid for atomizing the liquid fuel is supplied through 75 a tube or outer casing 21 surrounding said inner casing 20 and connected to the elbow by means of a threaded sleeve or union 22, said inner and outer casings having independent inlets, which are not shown in the drawing as the structure of the same is common in the art. 80

The compressed air or steam, or any other fluid used for the atomizing of the liquid fuel, is admitted into the casing 21 wherefrom it enters the passages 15 of the elbow 85 and fills the chamber 18. Then it enters the tip body 7 through apertures 19, from where it finds its outlet through the slot 14. The liquid fuel admitted through the inner cas- 90 ing 20 passes through the central passage 11 of the elbow into the tip 7, meeting the compressed fluid at the apertures 19 where it begins to intermingle with the fluid and is broken up into small particles before it 95 reaches the slot 14, when, due to the sudden expansion of the compressed fluid, the said liquid fuel is atomized into a spray shaped by the slot 14.

Having thus described my invention, I 100 claim as new and desire to secure by Letters Patent:

1. In a liquid fuel burner, a tip having funnel and cylindrically-shaped portions, said funnel portion having a liquid fuel inlet at the bottom thereof and a fluid inlet in the sides thereof, said cylindrical portion having an outlet for said fuel and fluid. 105

2. In a liquid fuel burner, a tip having a funnel portion provided with cylindrical extensions at its ends, one larger than the other, said tip having a liquid fuel inlet 110

- into the smaller cylindrical extension and a fluid inlet in the sides of said funnel portion, said tip having an outlet for said fuel and fluid in the lateral surface of the larger cylindrical portion.
3. In a liquid fuel burner, a tip comprising a funnel portion having cylindrical extensions at the ends thereof, the extension at the smaller end of said funnel portion forming the fuel inlet for said tip, said funnel portion having apertures in the sides thereof adjacent the smaller end of the funnel forming the fluid inlet into said tip; a plug for the cylindrical extension at the other end of the funnel, said latter cylindrical extension having a slot in the lateral surface thereof adjacent the plug forming an outlet for the fuel and fluid from said tip.
- 20 4. In a liquid fuel burner, a member hav-

ing a central liquid fuel passage and a fluid passage adjacent said fuel inlet; a tip associated with said member comprising a funnel portion having extensions at the ends thereof, the extension at the smaller end registering with the central passage and thereby forming the fuel inlet into said tip; a sleeve associated with said member adapted to surround the funnel portion of said tip and forming a fluid chamber thereabout, said funnel portion having means establishing communication between said chamber and tip.

In testimony whereof I have signed my name to this specification in the presence of two subscribing witnesses.

GEORGE EDMOND DENMAN.
